GAS BURNER, INCLUDING INTERNAL FUEL DISTRIBUTOR

James L. Raulston, South Pittsburg, Tenn.

Application February 25, 1947, Serial No. 730,812

1 Claim. (Cl. 158—114)

1

This invention relates to heating and more particularly to heating by the use of gas or the like.

It is an object of the invention to provide a burner for gas, of simple and inexpensive construction, and from which maximum heat can be obtained.

A further object of the invention is to provide a burner having a series of groups of burner ports supplied from a single manifold.

Another object of the invention is to provide a burner having raised ports so that increased secondary air will be supplied to the gas containing primary air for improving combustion without undesirable flashback, odors, and the like.

A further object of the invention is to provide a burner of sufficiently wide application that it is particularly adaptable for use, both as a space heater and in connection with a stove, furnace, or the like.

Further objects and advantages of the invention will be apparent from the following specification taken in conjunction with the accompanying drawing, wherein:

Fig. 1 is a front elevation with a portion broken away to show the burner in position;

Fig. 2, a vertical section; and

Fig. 3, a fragmentary perspective.

With continued reference to the drawing, there is shown in Fig. 1 a modern type space heater, including a base 10, a radiant housing 11, a guard rail 12, and radiants 13.

The radiants are of conventional construction and are supplied with combustible fluid in the form of a combination of gas and primary and secondary air from a burner constituting the essence of the present invention.

The burner is preferably a hollow, elongated structure and includes a manifold 14 to which gas is supplied from a line 15 through an adjusting valve 16, an air valve 17 for controlling the amount of air supplied to the gas prior to its passing into the mixing chamber 18 and ports 25 may be provided to support the radiants 13. Said burner is preferably a cast unitary structure but may be made by other means if desired.

Gas from the mixing chamber 18 is supplied to the manifold 14 and distributed therein to the several groups of raised ports 19. In order that all of the ports will be supplied a pair of longitudinal baffles 20 and 21 are provided extending substantially from one end of the manifold to the other. These baffles have their adjacent edges in parallel relation in order to con-

stitute a relatively narrow space or fuel slot between them through which and beyond the ends of which the gas may pass. In order that gas may pass around the ends of them, said baffles are reduced at their extremities by notches providing enlarged openings 22. These permit increased volume of gas to flow into the ends of the manifold and toward the center of the same between and above the baffles so that even distribution of the combustible mixture to the raised burner ports 19 is accomplished.

The ports 19 are defined by annular raised portions or bosses and are spaced apart sufficiently to allow circulation of air around them for combination with the mixture of air and gas discharged through the several ports and thus improve combustion.

Said ports are disposed in the upper wall or top of the burner, and are arranged in longitudinal spaced groups of three rows each, the intermediate row being staggered relative to the other rows.

Furthermore, both sides of the manifold 14, from the base of the ports 19, to a point below, 25 are provided with downwardly tapered or inclined surfaces 23 and 24 which will further improve combustion, as secondary air will reach the ports 19 unobstructed.

Two rows of ports have been employed; however, with ports 19 raised as in the present construction, an intermediate or third row of ports can be used and with improved results, including the spacing of the flame from the heated metal body of the burner so that cooling of the raised ports is accomplished and flashback is prevented.

It will be obvious to those skilled in the art that various changes may be made in the invention without departing from the spirit and scope thereof and therefor the invention is not limited by that which is shown in the drawing and described in the specification but only as indicated in the appended claim.

What is claimed is:

45 A burner comprising an elongated hollow manifold having a bottom and a substantially flat top with downwardly sloping side walls and ends, said side walls being substantially uniformly spaced throughout their length whereby the cross sectional area defined by said side walls and bottom is substantially uniform throughout the length of the manifold, a first row of bosses located on said top adjacent one downwardly sloping side wall, a second row of bosses on said top 50 adjacent the other downwardly sloping side wall,

each boss of the second row being opposite the corresponding boss on the first row, a third row of bosses located on said top intermediate the first and second rows with each boss of the third row in staggered relation to the bosses of the first and second rows, each of said bosses having a port extending therethrough and through said top and providing communication with the manifold, a first elongated baffle within said manifold having one edge abutting one side of said manifold and secured thereto and having its opposite edge extending towards the other side, a second elongated baffle within said manifold having one edge abutting the other side of the manifold and secured thereto and its other edge extending towards said one side, said baffles extending substantially the full length of said manifold and

5 defining a fuel slot therebetween, said baffles being notched adjacent their ends forming enlarged openings for the passage of fuel, and said manifold having a fuel inlet below said baffles.

JAMES L. RAULSTON.

defining a fuel slot therebetween, said baffles being notched adjacent their ends forming enlarged openings for the passage of fuel, and said manifold having a fuel inlet below said baffles.
